JUMPER FOR INTERCONNECTING SPACED ELECTRIC TERMINALS

Thomas E. Curtis, Hampton, Ga., assignor to Southern States Equipment Corporation, a corporation of Georgia

Application June 14, 1952, Serial No. 293,499

1 Claim. (Cl. 339—19)

This invention relates to electric circuit-breaking devices such as switches, fuses and the like, particularly those for outdoor use on high voltage circuits. This application is a continuation in part of my application Serial No. 106,345 filed July 23, 1949 now Patent 2,689,944, dated September 21, 1954. One object of the invention is to provide jumper means whereby the mechanical functioning of a switch may be tested while the circuit remains uninterrupted. Another object is to provide jumper means whereby a high voltage fuse may be removed for inspection or replacement without interruption of the load normally carried by the fuse, protection being afforded by a backup breaker or fuse while the fuse which has been removed is out of service. Another object is to provide jumper means whereby an automatic switching system involving several circuit breaking devices can be tested without interrupting any of the circuits. Another object is to provide a jumper which is simple and low in cost and which can be used in conjunction with many different types of circuit breakers, which resists accidental misplacement, which provides high pressure contacts and which can remain in use for long periods if desired. Another object is to provide a jumper which is single and low in cost and which can be used in conjunction with many different types of circuit breakers, which resists accidental misplacement, which provides high pressure contacts and which can remain in use for long periods if desired. Another object is to provide a long insulating handle by a joint which holds jumper and handle together in straight stiff alignment, but which joint is at any time readily engageable or separable at will. Another object is to provide new members adaptable for use with existing equipment, thereby providing supporting means for the jumper.

Referring to the drawings:

Figure 1 shows one form of jumper in which this invention is embodied.

Figure 2 shows a modified form of the upper end of a similar jumper.

Figure 3 shows a modified form of the lower end of such a jumper.

Figure 4 shows the top end of a switch stick used for handling the jumper.

Figures 5 and 6 show a jumper being placed in service.

Figure 7 in larger scale and in partial section shows details of insulator, conducting terminal and jumper support.

Figures 8 and 9 show two positions in which the bolt holes in the top of an insulator may be placed.

Figures 10 and 11 show two views of the jumper support which is attachable to an insulator for holding a jumper thereto.

Referring to Figure 1, the jumper 1 has an upper jumper contact 2 fastened to a tube 3 by screws 4, 4. The upper contact 2 may be made in any desired form, but as here shown, it is annular. In the lower end of contact 2 and inside the tube is hole 5. One end of ex-

2

tension spring 6 is hooked in hole 5 and the lower end of spring 6 is engaged with hook 7 which is part of link 8. The lower end 9 of link 8 is hooked in hole 10, which is in the top part of lower jumper contact 11. Contact 11 includes also an upper cylindrical portion 11a which fits loosely inside tube 3, a ring portion 12, a stop collar 13, and a lower portion 14 which is a hollow cylinder open at the bottom. A flexible conducting shunt 15 electrically connects contact 2 with contact 11 with enough slack to allow considerable longitudinal motion of contact 11. When assembled, as shown in Figure 1, spring 6 exerts a slight upward pull on contact 11, holding stop 13 against the lower end of tube 3.

Figure 3 shows a modified form 16 of the lower jumper contact. This is similar to contact 11 except that instead of only one ring 12, it has two spaced rings 17, 18. The lower part of contact 16 is the same as cylinder 14 in Figure 1, and the same numerals are used to designate the corresponding parts of contact 16.

Figure 4 shows the top part of one form of switch stick which is suitable for operating the jumper. The insulating wooden stick 19 may be whatever length is needed in order that a man on the ground may easily reach the equipment above him. Such a stick may have a length of fifteen feet or even more. On top of the stick 19 is affixed the metal head 20 which includes a cylindrical portion which fits easily into the cylinder 14 of the jumper, the conical top of head 20 acting as a guide. A finger 21 extends laterally from the side of head 20, spaced well below the top.

In the side of cylinder 14, at the bottom, is an angular slot 22 which is engageable with finger 21 by inserting head 20 into cylinder 14 and then rotating stick 19, to form a bayonet-type joint between stick 19 and jumper contact 11. When so engaged the stick 18 and jumper 1 form a unitary assembly with all parts held stiffly in alignment with one another.

Slight enlargements 22' at the end of slot 22 tend to prevent unintentional rotation of the jumper 1 when the finger 21 is engaged with the slot, both when the weight of the jumper is borne by the finger and also when the finger is pulling downwardly to stress spring 6.

Figures 5 and 6 show how the jumper is placed in service. Two insulators 23, 24 support, respectively, terminals 25, 26 which are normally connected together electrically by the fuse, switch arm, or other circuit breaker 27. Inserted between each of the insulators 23, 24 and its respective terminal 25, 26 is a jumper support 28', 29. These supports are identical and they are shown in larger scale in Figures 10 and 11. They are reversible and they are positioned so that the hook on the upper support points upwardly and the hook on the lower support points downwardly.

Supported by stick 19, the jumper is lifted up and the jumper contact 2 is engaged with support 28'. Then an axial pull downwardly on stick 19 is transmitted through the finger 21 to lower jumper contact 11, partly withdrawing contact 11 from tube 3 and stressing spring 6. Stick and jumper are then moved sidewise so that ring 12 is passed over support 29. Stick 19 is then raised. The space between supports 28, 29 is slightly greater than the normal space between contact 2 and ring 12, and so the full force of spring 6 develops good contact pressures between the supports and the two jumper contacts. The stick 19 is then rotated and lowered, thereby disconnecting the bayonet-type joint and allowing the long switch stick to be completely removed.

An electrical path of adequate capacity is thereby established between the terminals 25 and 26; and the fuse, switch arm, or other circuit breaking device, can be removed, replaced, and operated at will without affecting the current flowing between terminals 25 and 26.

3

Thus installed, as shown in Figure 6, the jumper is entirely out of the way and it can be left in service for a considerable time if necessary. The hook-and-ring holding means together with the strong pressures caused by spring 6 tend to preclude any accidental misplacement of the jumper. The switch stick is of such length as to enable a man standing on the ground to operate the equipment above him easily; and therefore if not removed the switch stick would be a serious hazard. Figure 7 in larger scale gives a side view of details of one insulator and its adjacent members. The insulator 23 has a metal cap 30 affixed to it and bolts 31, 31 are screwed into or otherwise engaged with cap 30 to hold terminal 25 securely to the insulator.

Figures 10 and 11 show jumper support 28, which consists of a thin flat plate 34 with free passage for bolts therethrough, and integral with the plate the contact making hook 28'. The plate 34 may readily be inserted between insulator cap 30 and terminal 25, so that bolts 31-31 will then hold both support 28 and terminal 25 securely to insulator 23. Alternatively, two bolts 31, 31 may be used instead of four in securing terminal and support to the insulator. When the insulator is positioned as indicated in Figure 8, bolts will pass through holes 32-32; when the insulator is positioned as in Figure 9, bolts 25 will pass through holes 33-33.

Figure 2 shows a modified form of the spring-biased contact and their associated members. To the upper jumper contact 35 is fastened the outer tube 36 by means of screws 37, 37; and to the lower jumper contact 38 is fastened the inner tube 39 by means of screws 40, 40. Slots 41, 41 are cut in opposite sides of tube 39, and screws 42, 42 are screwed into the walls of tube 36 with their inner ends projecting into slots 41, 41. Tube 39 makes a sliding fit inside of tube 36, and screws 42, 42 limit this sliding motion of tube 39.

The close-coil tension spring 43 is secured at its top end by being screwed over the helical groove in the lower end of contact 35. The lower end of spring 43 is similarly secured to the upper end of lower contact 38. Flexible conductor 44 is secured to both contacts 35 and 38, keeping them electrically connected regardless of their relative positions.

The long sleeve fit between tubes 36 and 39, holds contacts 35 and 38 always in good alignment, and screws 42, 42 prevent any relative twisting motion while allowing easy longitudinal motion between the two contacts. All parts are so proportioned that when in use the slots 41, 41 are covered by tube 36, and so the interior of the tubes is closed against the entrance of insects.

Normal positions of all parts are as indicated in Figure 2, and dimensions are such that when in use spring 43 is somewhat extended so that good contact pressures are imposed by the jumper contacts against the two jumper supports.

The spacing of bolts on such switch-type insulators generally conforms to previously determined standards, but insulators may be positioned so that the bolts may be located either according to Figure 8 or Figure 9. The design of jumper support shown in Figure 10 makes the support applicable for use with either arrangement of the bolts 31, 31. Also the symmetrical design of the jumper support as shown makes it suitable for mounting on either the right or the left side of the insulator and with the hook pointed either upwardly or downwardly. For larger insulators with differently located bolts, different jumper support members may be provided. And if desired such jumper supports may be made as integral parts of electrical terminals such as 25 and 26. For each of the various voltages, the spacing of insulators conforms to standards that are currently known and generally accepted, the higher voltage taking greater spacing between the insulators. And in order that the same jumper may be used on two or more voltages for which the insulator spacings are not too different, one contact of the jumper may have two or more rings as shown in Figure 3. For the lower voltage, the rings 17 would be used; for the higher voltage, the ring 18 would make contact with the lower jumper support 29.

I claim:

A jumper for interconnecting a pair of spaced electric terminals comprising a first contact engageable with one of the terminals and having a threaded portion, a second contact engageable with the other terminal and also having a threaded portion, a coil spring arranged with its end coils respectively in threaded engagement with the threaded portions of said contacts, said spring being effective to establish a predetermined contact pressure between each contact and its associated terminal, a sleeve affixed to each contact, said sleeves being telescopically related to form an enclosure for said spring, a longitudinal slot in one of said sleeves, and a pin secured in the other of said sleeves and disposed in said slot, engagement of said pin with the ends of said slot being respectively determinative of the minimum and maximum spacing between said contacts.
